UNITED STATES PATENT OFFICE.

ALBERT M. KNAPP, OF PORTLAND, OREGON.

CAR-COUPLING.

No. 853,017.

Specification of Letters Patent.

Patented May 7, 1907.

Application filed February 21, 1907. Serial No. 358,539.

To all whom it may concern:

Be it known that I, ALBERT M. KNAPP, a citizen of the United States, and a resident of Portland, in the county of Multnomah and State of Oregon, have invented an Improvement in Car-Couplings, of which the following is a specification.

My invention is an improvement in car couplings of the Janney type. The curved locking arms, or so-called "knuckles," of such couplings, are subject to wear, owing to lateral and vertical motion of the cars, so that they are ultimately weakened and rendered useless, and must then be discarded and new ones substituted. To avoid this and the attendant expense, it has been proposed to provide the inner sides or faces of the knuckles with a removable wear-piece which can be discarded when worn out, and a new one substituted without the necessity of doing away with the entire knuckle.

My invention is an improvement in this line, and is embodied in the novel construction, arrangement, and combination of parts hereinafter described and claimed.

In the accompanying drawing, Figure 1 is a plan view of the main portion of a coupling arm, or "knuckle." Fig. 2 is a vertical section on the line 2—2 of Fig. 1. Fig. 3 is a horizontal section on the line 3—3 of Fig. 2. Fig. 4 is a perspective view of the filling and wear-piece applied to the knuckle. Fig. 5 is a perspective view showing the recess in the knuckle which is filled by the removable wear-piece.

The knuckle proper A may be constructed in the usual form, and, as shown best in Fig. 5, it is provided on the inner side, adjacent to the end of its nose, with a vertical groove or recess whose sides *a* are inclined outward, the back *a'* being flat. At the center of this vertical recess *a* is formed a smaller one *a''*, which, as shown in Fig. 2, extends inward a short distance. The filling and wear-piece B, which is shown detached in Fig. 4, has a form corresponding to the vertical and central recesses before described. That is to say, the sides *b* of the wear-piece are inclined corresponding to the sides *a* of the vertical recess, and a lug *b'* projects from the flat back of the wear-piece and is in the form of a truncated wedge, whereby it is adapted to

enter the central recess *a''*. In rear of the main vertical recess in the nose of the knuckle, there is formed an opening *a''* adapted to receive a wedge-shape key C—see Fig. 2—and this recess is in alignment with a vertical opening *b''* in the lug *b'* of the wear-piece B.

It will be seen that when the wear-piece is applied to the knuckle, as indicated in Figs. 1, 2, and 3, it fits closely at all points in the main or vertical recess, but the back of the apertured lug *b'* does not extend to or come in contact with the back of the central recess *a'* in the knuckle. It will be further noted that the back or rear side of the aperture *b''* in the lug *b'* is not exactly in alignment with the back of the key seat—see Fig. 2—and, consequently, when the wedge-key C is inserted it is in contact with the back of the lug aperture and therefore draws the wear-piece B firmly to its place, where it is held securely until worn out. If, however, from any cause, slight looseness should at any time occur, the wear-piece may be easily tightened by a slight blow on the head of the wedge-key C. I thus provide the knuckle A with a wear-piece B at the point where the greatest wear occurs, and the knuckle is therefore not reduced or weakened at the point of curvature of the same where the greatest strength is required. When the base B has become worn to such a degree as to require it, it may be easily detached and a new one substituted therefor. It is preferably constructed of wrought iron, and may be produced at very small cost.

What I claim is—

1. The combination, with a knuckle having a vertical recess whose sides are inclined outward, and a small central recess extending inward from the main recess, and a key-seat in rear of the main recess but aligned with the central one, of a filling and wear-piece whose sides are inclined corresponding to the main recess, and provided on its back with an apertured lug which extends rearward a less distance than the depth of the central recess in the knuckle, and a wedge-key adapted for insertion in the key-seat in the knuckle and through the coincident opening in the lug of the wear-piece, as shown and described.
2. The combination, with a knuckle having its nose provided on the inner side with

a vertical recess having a flat back and outwardly inclined sides, a central recess extending inward from the main one and having also inclined sides, and a vertical key-
5 seat formed in rear of the main recess and in alinement with the central one, of the wear-piece having a flat back and inclined sides, and a lug provided with a central aperture

and having inclined sides, and a key for securing the wear-piece in place, substantially as described.

ALBERT M. KNAPP.
